UNITED STATES PATENT OFFICE.

THOMAS O. POTTER, OF BOSTON, MASSACHUSETTS.

BUCKLE.

SPECIFICATION forming part of Letters Patent No. 291,225, dated January 1, 1884.

Application filed October 22, 1883. (No model.)

To all whom it may concern:

Be it known that I, THOMAS O. POTTER, of Boston, in the county of Suffolk and State of Massachusetts, a citizen of the United States, 5 have invented a certain new and useful Improvement in Buckles, of which the following is a full, clear, and exact description, reference being had to the accompanying drawings, forming a part of this specification, in explaining its nature, in which—

Figure 1 is a perspective view of a buckle containing my invention. Fig. 2 is a view in perspective of the end of a part of the jaw. Fig. 3 is a view in perspective of the end of a part 15 of the buckle back or body. Figs. 4 and 5 are plan views of the buckle, and Figs. 6 and 7 sections on the line xx of Fig. 1.

The invention relates especially to the specific means herein described for securing the 20 jaw of the buckle to the body or back thereof.

Referring to the drawings, a represents the body or back of the buckle. It may have any suitable shape and be provided with a slot, a' , through which the end of the strap may be 25 passed in fastening the buckle in place. It may have in addition thereto a hook, such as described in former patents granted to me on this subject, or any other suitable form. This body is struck up from a sheet-metal blank of 30 suitable shape and having ears a^2 integral therewith. These ears are kept at right angle to the body or back of the buckle, as shown in Figs. 1 and 3, and a pivot, a^3 , is formed upon the inner side of each by striking from the 35 metal of the ear a section of the central portion thereof, as represented—that is, the portion of the central part of the ear is cut or punched upon its sides and end nearest the back and turned inwardly therefrom, so that 40 its point of connection with the ear is near the outer end of the ear, and the pivot is thus provided from the body of the ear located in the proper position, and the strength of the ear is not diminished. The jaw b of the buckle is 45 much like the jaw of ordinary buckles of this description, with the exception that the ears b' thereof are provided with holes b^2 , through which the pivots which project inward from the ears a^2 of the back extend. Of course it is

not necessary that the pivots be connected 50 with the ears near the upper end or top thereof, as shown by the drawings, because they can project from either side thereof or from a point near the center or under section thereof without departing from the spirit of the invention; but in such case it would be necessary to have the ear somewhat longer than shown in the drawings. The ends of the pivot may be turned downward toward the body or back of the buckle, if desired, as shown in Figs. 60 5 and 7, and thereby lock the jaw and back or body securely together, so that lateral strain upon the jaw or back shall not disengage the jaw from the pivots. This construction is cheap and strong and desirable, in that the 65 pivots, instead of projecting outwardly from the jaw through the holes in the ears of the back, extend inwardly from the back, and are thereby so located that they cannot engage with or catch the clothing, and as the ears of 70 the back are made curved and rounded, as are also the outer edges of the jaw, a very smooth and rounded finish is obtained upon the outer edges of the buckle.

Having thus fully described my invention, I 75 claim and desire to secure by Letters Patent of the United States—

1. In a buckle, the combination of the back or body having the ears a^2 , from which the pivots a^3 are formed by striking or bending 80 inward the portion of the body of the ear described, with the jaw b , having the ears b' , through holes in which the pivots a^3 extend, all substantially as and for the purposes specified. 85

2. The combination, in a buckle, of the jaw b , having the ears b' , provided with holes b^2 , and the body a , having the ears a^2 , provided with extensions or pivots a^3 , formed therefrom, as described, and extended through said holes 90 and then bent or curved downwardly to lock the jaw and back together, all substantially as and for the purposes described. 90

THOMAS O. POTTER.
